UNITED STATES PATENT OFFICE.

STANLEY M. UDALE, OF DETROIT, MICHIGAN, ASSIGNOR TO EARL HOLLEY, OF DETROIT, MICHIGAN.

PISTON.

Application filed November 15, 1924. Serial No. 750,066.

This invention relates to an improved piston. The object of this invention is to reduce both the cost of manufacture and the weight of ordinary gray iron pistons.

5 The difficulty heretofore experienced in casting gray iron pistons has been that any attempt to lighten the weight of the piston has involved the use of loose pieces in the core box which prevented the production 10 of cheap pistons, as one of the principal items in the cost of a piston is the core.

In order that the core may be made cheaply, as for example by the means and methods disclosed in the co-pending application of Alexander Anderson, Serial No. 694,918, filed Feb. 25, 1924, it is necessary that it should be formed in a two-part core box, the two halves of which should be drawn or separated on a plane at right 20 angles to the axis of the wrist pin bosses. All light weight pistons which I am familiar with have been provided with various stiffening ribs or webs which necessitated the use of loose pieces, which seriously interfered 25 with economical production. This improved piston is free from this objection.

A further object of this invention is to arrange so that the mold in which the core is placed shall be free from all projections 30 or recesses. That is to say, that the wall of the mold shall be substantially smooth, the reason being that it is intended that these pistons shall be cast in the molds shown in the patent to Meloche, #1,502,861, and it 35 has been found that the life of the mold is greatly increased by avoiding any sharp corners or recesses on the surface of the mold.

Figure 1 shows a cross sectional elevation on the plane 1—1 of Figure 3. 40

Figure 2 shows in elevation a side view of the piston.

Figure 3 shows a plan view of the piston.

Figure 4 is a cross sectional plan view taken on the plane 4—4 of Figure 2. 45

In the figures, A is the piston head, B is the upper portion of the piston skirt provided with the usual number of piston ring grooves. C D are the wrist pin bosses. E F are two horizontal flanges connecting the bosses C and D and extending around the piston. G and H are the two side wall bearing strips. These strips are made in the form of the letter H. 50

I and J are recesses on the outside of the piston adjacent the bosses. K is the lower portion of the skirt connected to the bosses C and D by ribs L and M. This lower portion of the skirt K is formed in the shape of a channel so that it may be sufficiently stiff 60 to retain its shape. Vertical ribs N O P Q extend from the bosses C D to the piston head A, providing the support for the piston head. 55

What I claim is:—

A cutaway piston comprising a piston head, an upper skirt connected thereto, two piston pin bosses, webs extending from said bosses to said head, a lower skirt, bearing strips connected thereto and extending to 70 the upper skirt, a horizontal circumferential rib extending from the bosses to the bearing strips.

In testimony whereof I affix my signature.

STANLEY M. UDALE.
